UNITED STATES PATENT OFFICE.

MARK MUSGREAVE, OF PHILADELPHIA, PENNSYLVANIA.

WOOL-WASHING MACHINE.

SPECIFICATION forming part of Letters Patent No. 554,289, dated February 11, 1896.

Application filed August 23, 1894. Serial No. 521,077. (No model.)

To all whom it may concern:

Be it known that I, MARK MUSGREAVE, of the city and county of Philadelphia and State of Pennsylvania, have invented an Improvement in Wool Washing or Scouring Machines, of which the following is a specification.

My invention relates to wool washing or scouring machines; and it consists of certain improvements which are fully set forth in the following specification and are shown in the accompanying drawings.

My invention relates to a wool-washing machine in which the wool is carried through the liquor in a suitable tank by means of a traveling conveyer provided with depending rakes or frames which act upon the wool.

It is the object of my invention to produce a machine of this character of compact, simple and economical construction, and to enable the wool to be more positively and easily carried through the liquor and delivered to the squeeze-rolls. For this purpose I employ a series of rakes loosely connected or hinged to a traveling conveyer, so as to be normally carried through the liquor and delivered to the squeeze-rolls. When the rakes pass from the guide they are free to swing into a vertical position by gravity and to remain in that position as the conveyer travels. The rakes remain rigid until they reach the squeeze-rolls, so that they will act positively upon the wool to move it along.

When the rakes pass from the guide they are free to swing into a vertical position by gravity and to remain in that position as the conveyer travels. The rakes remain rigid until they deliver the wool to the squeeze-rolls and then are released and swing back into a vertical position or beyond a vertical position. The rakes thus remain rigid until they deliver the wool directly to the squeeze-rolls, and as they are released and allowed to hang vertically or substantially so after they have delivered the wool to the rolls they may move closer to them and will not carry the wool beyond the rolls. As the rakes hang vertically as the conveyer passes about the guides instead of projecting radially, as would be the case if they were rigidly connected with the conveyer, it is apparent that a shorter and more compact machine may be employed.

My invention also embraces novel construc-

tions and combinations, which are hereinafter more fully described and claimed.

I shall now refer to the accompanying drawings for the purpose of more particularly describing my improvements, in which—

Figure 1 is a side elevation, with part in vertical section, of a wool washing or scouring machine embodying my invention. Fig. 2 is a perspective view of part of the conveyer and guides. Fig. 3 is a similar view of the wool-submerging roller or drum, and Fig. 4 is a detail perspective view of part of the chain and rake of the conveyer.

A is any suitable tank to contain the liquor.

B is a perforated diaphragm therein, through which the liquor may permeate.

C C are the squeeze-rollers at the delivery end of the tank. In the drawings I have shown the rear end of the diaphragm B inclining upward to the squeeze-rollers.

D are a pair of endless chains which carry the rakes E and travel about suitable pairs of spocket-wheels F F' F² F³, of which preferably one pair, as F, is operated to drive the chain. The chains travel for a portion of their length over the tank A so as to submerge the rakes E in the liquor.

The rakes E are pivotally connected with the chains D, as by the lateral studs d carried by links of the chains and engaging holes g in elongated heads or blocks G on the ends of the upper portion of the rakes, or vice versa. These blocks or heads G are adapted to enter ways or guides H, arranged along the top of the tank A and adapted to lock the rakes against movement on their pivots d, while the blocks are traveling through ways H. I prefer to make the ends of the blocks or heads with curved or inclined faces h, so as to reduce friction and permit the blocks to easily enter the ways and turn through the bend therein, where the ways incline up to correspond with the inclination of the diaphragm B to the rollers C C.

The front entrance to the ways H H is preferably enlarged, as at f, to receive the heads G.

The rakes E are provided with the depending portions or fingers I, which extend down close to or in contact with the face of the diaphragm B. As the blocks or heads G enter the ways H and become locked against movement on their pivots, the rakes are held fixed

and remain so until the blocks G pass out of the ways H at the rear end of the machine. The rakes are thus locked while they travel over the diaphragm B, and they will carry 5 the wool over the diaphragm and deliver it to the squeeze-rollers C C. When the blocks G pass from the ways H the rakes become unlocked and are permitted to swing upon their pivots, and to hang freely until they again 10 enter the forward ends of the ways. When released the rakes may assume a position slightly to the rear of a vertical line. The rakes may pass freely between the pairs of 15 spocket-wheels F F' F² F³, which are preferably supported on independent brackets on each side of the machine. It will be observed that as the rakes pass through the inclined portion of the ways they are thrown from a 20 vertical position so that their ends travel in an upwardly inclining position to the squeeze-rolls, thus carrying the wool out of the liquor and delivering it directly to the rolls. This movement of the rakes directly to the bite of 25 the rolls C C is possible because the rakes are released and permitted to assume a more or less vertical position immediately after they have reached the rolls C C.

The release of the rakes E E, so that they assume a more or less vertical position, prevents 30 them from carrying the wool beyond the squeeze-rolls, as the wool will slip off the fingers I I by gravity.

By supporting the rakes so that they will swing back slightly beyond the vertical line, the freeing of the rake-fingers from such 35 portions of wool as may tend to adhere may be more effectively accomplished.

I have shown the upper squeeze-roller C carried in spring-pressed bearings c depressed 40 by a lever or levers J resting upon the bearings c and having its free end connected by an adjustable rod K with a leaf-spring L on the frame of the tank A. The upper end of the rod K passes through the lever J, and a 45 spring M is interposed between the upper end of the rod and the lever. The tension of the spring M may be regulated by a nut H on the rod.

The sprocket-wheels F may be driven in 50 any suitable manner. I have shown them operated from a shaft O through sprocket-wheels P P', chain P² and pairs of gears P³ P⁴. The gears P³ may be carried on a common shaft p, and may each gear with a gear P⁴ 55 connected with one of the sprocket-wheels F.

Q is a submerging-roller journaled over the diaphragm B in the front of the tank, which is extended beyond the line of travel of the chains D. This submerging-roller is provided 60 with radial wings R curved in the opposite direction to the direction of rotation of the roller. The roller Q is journaled so that the wings or fingers will pass into the liquor in the tank. The wool which is thrown into the 65 front end of the tank is depressed by the wings R, and is submerged in the liquor. Thus the concave face of the wings

acts upon the wool and the wool will not adhere to the wing and be lifted from the liquor as the same rises, but will freely slip from the concave face. The wings R are shown continuous across the length of the roller.

The construction and use of the submerging-roller are not material to my invention.

The wool which is submerged by the roller 75 Q falls upon the diaphragm and rests there until it is taken by the rakes E. It is then carried forward upon the diaphragm through the squeeze-rools C C, as has been described.

The roller Q may be rotated in any suitable manner, as by a sprocket-chain S driven by a sprocket-wheel T on the journal of the sprocket-wheel F² and passing about a sprocket-wheel T' on the shaft of the roller Q.

The details of construction shown may be 85 varied without departing from the invention.

Having now described my invention, what I claim as new, and desire to secure by Letters Patent, is—

1. In a wool washing or scouring machine, 90 the combination with the tank and squeeze-rolls, of a traveling conveyer moving over the tank, a series of loosely-supported depending rakes carried by the conveyer, a rake-locking guide arranged along the tank and extending 95 up to a point adjacent to the squeeze-rolls adapted to lock the loosely-supported rakes against movement with reference to the conveyer while they are being carried up to the squeeze-rolls, whereby the rakes may be 100 caused to convey the material in the tank directly to the squeeze-rolls, and may then be released or unlocked from the guides.

2. In a wool washing or scouring machine, 105 the combination with the tank and squeeze-rolls, of a guide within the tank extending up to the squeeze-rolls, a traveling conveyer moving over the tank, a series of loosely-supported depending rakes carried by the conveyer, a guide arranged along the tank and 110 extending up to a point adjacent to the squeeze-rolls and over the guide within the tank leading to the squeeze-rolls, adapted to lock the loosely-supported rakes against movement with reference to the conveyer 115 while they are being carried up to the squeeze-rolls, whereby the rakes may be caused to convey the material in the tank directly to the squeeze-rolls, and may then be released or unlocked from the guides.

3. In a wool washing or scouring machine, 120 the combination with the tank and squeeze-rolls, of a perforated diaphragm within the tank having an upwardly-extending portion to the squeeze-rolls, a traveling conveyer, a 125 series of loosely-supported rakes carried by the conveyer and depending into the tank when carried over it, and a guide arranged over the tank to lock the rakes against movement with reference to the conveyer when 130 traveling over the tank, having an upward extension over the upward extension of the diaphragm to the squeeze-rolls, whereby the rakes are locked by said guide up to the point

of delivery to said squeeze-rolls and are then unlocked and permitted to swing into normal position under the action of gravity.

4. In a wool washing and scouring machine the combination of a tank, a pair of squeeze-rollers at one end of the tank, a perforated diaphragm within the tank below the liquor-level and inclining upward at one end above the liquor-level to the squeeze-rolls, a conveyer arranged to travel over the tank provided with a series of depending rakes loosely supported by the conveyer at their upper ends, and a guide arranged along the tank above the perforated diaphragm and having

an upwardly-inclining portion extending 15 above the upwardly-inclining portion of the diaphragm, adapted to act upon the rakes and lock them against movement with reference to the conveyer while they are traveling over the perforated diaphragm and until they de- 20 liver the wool to the squeeze-rolls.

In testimony of which invention I have hereunto set my hand.

MARK MUSGREAVE.
